(**) Term: **14 Years**

(57) **CLAIM**

(21) Appl. No.: **29/167,864**

The ornamental design for a white balance adjusting tube for electronic endoscope, as shown.

(22) Filed: **Sep. 24, 2002**

DESCRIPTION

(30) **Foreign Application Priority Data**

Mar. 25, 2002 (JP) 2002-007659

(51) LOC (7) Cl. **24-02**

(52) U.S. Cl. **D24/138**

(58) **Field of Search** D24/138, 137, D24/107, 127, 128, 140; 348/223.1, 655, 68, 376; 600/132, 134, 453, 459, 461, 160

(56) **References Cited**

FIG. 1 is a perspective view of the top, front and left side of a white balance adjusting tube for electronic endoscope showing my new design;
FIG. 2 is a left side elevational view thereof;
FIG. 3 is a top plan view thereof;
FIG. 4 is a rear elevational view thereof;
FIG. 5 is a front elevational view thereof;
FIG. 6 is a right side elevational view thereof; and,
FIG. 7 is a bottom plan view thereof.
